DISPLAY DEVICE

John A. Kern, Chicago, Ill., assignor to The W. J. McCahan Sugar Refining & Molasses Co., Philadelphia, Pa., a corporation of Delaware

Application September 13, 1937, Serial No. 163,623

6 Claims. (Cl. 40—126)

This invention relates in general to display devices, and more particularly to a device for providing a continuous stream of a granular substance for advertising display purposes.

5 A principal object of the invention is the provision of an advertising display device which functions to provide a continuous stream of granular material flowing from a delivery unit to a receiving unit, which is adapted to attract 10 attention by appearing to constitute a delivery unit of limited capacity which delivers a steady and apparently inexhaustible flow of the granular material.

15 Another important object of the invention is the provision in such a device of a delivery unit which has the outward appearance of a standard package or carton normally used for marketing the particular granular material.

20 A further object of the invention is the provision of a receiving unit in such a device which visibly retains a predetermined quantity of the granular material delivered thereto at all times by receiving a continuous flow of the material while invisibly discharging the material at the 25 same rate at which it is received.

25 Numerous other objects and advantages of the invention will be apparent as it is better understood from the following description, which, when taken in connection with the accompanying drawings, discloses a preferred embodiment thereof.

In the drawings,

30 Figure 1 is a front elevational view of a device embodying the features of the instant invention;

Fig. 2 is a side elevational view of the device of Fig. 1;

Fig. 3 is a detail sectional view taken substantially on the line 3—3 of Fig. 2;

40 Fig. 4 is a vertical sectional view through the receiving unit taken substantially on the line 4—4 of Fig. 2;

Fig. 5 is a vertical sectional view through the upper portion of the delivery unit taken substantially on the line 5—5 of Fig. 1; and

45 Fig. 6 is a detail vertical sectional view, with parts broken away, taken substantially on the line 6—6 of Fig. 1.

50 Referring more particularly to the drawings, reference numeral 11 indicates a hollow casing forming a base for the instant device which is formed in any desired manner from sheet metal, or any other suitable material. An elongated hollow housing 12 is provided at the rear end of the casing 11 and upstanding therefrom, which

is adapted to support an angularly disposed hollow casing or delivery unit 13 at its upper end. A receiving unit, indicated generally by reference numeral 14 is removably mounted, in a manner to be later more fully described, on the 5 casing 11 directly below the forward or lower end of the delivery unit 13.

Mounted upon the base member of the casing 11 (Fig. 6) by means of a suitable bracket 15 is an electric motor 16 having a worm gear 17 secured to the outer end of the shaft thereof. The worm 17 meshes with a gear 18 which is mounted for rotation in any suitable manner upon one of a pair of horizontally disposed supporting brackets 19, which are secured to the rear wall 15 of the casing 11. The gear 18 comprises one of a train of driving gears which also includes a gear 21 rigidly secured to a shaft 22 journaled in a pair of bearing brackets 23 which are supported in any suitable manner by the brackets 20 19. Rigidly secured to the shaft 22 intermediate its end is a sprocket wheel 24 (shown in broken lines in Fig. 6) which is adapted to drive an endless chain 25 having a plurality of scoops or buckets 26 secured thereto in the usual manner.

Referring to Figs. 3 and 5, the chain 25 meshes with an upper sprocket wheel 27 similar to the sprocket 24 adjacent the upper end of the housing 12 which is secured to a shaft 28. The shaft 28 30 is journaled for rotation in a pair of suitable brackets 29 which are secured to the rear wall of the housing 12 in any suitable manner. Disposed within the housing 12 is an open-ended hollow casing 31 which surrounds the major 35 portion of the chain conveyor 25, 26 and is secured to the rear wall of the housing 12 by suitable brackets 32. It will thus be apparent that the motor 16 will drive the chain conveyor 25, 26 through the agency of the worm 17, the gear 40 train which includes the gears 18 and 21, and the driving sprocket wheel 24.

The bottom wall 33 of the hollow casing or delivery unit 13 is provided with a suitable aperture 34 through which the upper end of the 45 chain conveyor 25, 26 extends, as well as the supporting brackets 29. The forward portion of the aperture 34 closely surrounds the buckets 26 of the conveyor as they descend at the forward side of the conveyor during its operation. 50

In this manner, any material carried by the buckets 26 is dumped onto the angularly disposed bottom wall 33 of the delivery unit 13. The forward portion of the unit 13 is provided with a pair of auxiliary side walls 35 extending from 55

a point adjacent the forward end of the aperture 34 to the front wall 36 of the delivery unit 13 and converging toward each other at their forward ends. A delivery spout in the form of a short tube 37 is mounted in the front wall 36 of the unit 13 between the converging ends of the auxiliary walls 35.

The receiving unit 14, with particular reference being had to Fig. 4, comprises a hollow base member 38, a dome-shaped spacing member 39 mounted thereon and a hollow receiving bowl 41 supported by the member 39. Centrally disposed relative to these members and extending vertically therethrough is a hollow tubular member 42 which is open at its lower end and closed at its upper end, and is provided adjacent its upper end with a plurality of circumferentially spaced slots or apertures 43. The tube 42 is secured in any suitable manner to the hollow members 38, 39 and 41 to provide a unitary structure which is adapted to be removably positioned upon the upper surface of the hollow casing or base member 11. The top wall of the casing 11 is provided with an aperture 44 through which the lower end 25 of the tube 42 extends to properly position the receiving unit 14 under the spout 37 of the delivery unit 13. Within the bowl 41, a substantially conical plate 45 is disposed which is secured in any suitable manner at its lower end to the tube 42 and contacts the inner surface of the bowl 41 at its upper edge portion. A circular plate 46 is positioned within the bowl 41 directly adjacent the upper end of the conical plate 45 with its circumferential edge terminating a short distance 35 from the upper edge of the plate 45 and the inner surface of the bowl 41 to provide an annular recess 47 therebetween. A hollow spacing tube 48 is disposed between the upper end of the tube 42 and the plate 46 to properly position the latter, and the plate 46 is rigidly secured in this position by means of a bolt 49 which extends downwardly through the plate 46 and the spacer tube 48 and is screwed into a suitable threaded aperture in the upper end of the tube 42.

When the receiving unit 14 is mounted upon the casing 11 with the tube 42 extending through the aperture 44 in the upper wall of the casing, the lower end of the tube 42 extends downwardly into the open upper end of a hollow receiving hopper 51, which is best shown in Fig. 6. The hopper 51 is supported within the casing 11 by means of suitable brackets, or the like, 52. The lower end of the hopper 51 is truncated and is closed by a suitable bottom plate 53 which slopes downwardly toward the lower end of the casing 31 surrounding the chain conveyer 25, 26. A hollow chute 54 is secured at its upper end to the lower end of the hopper 51, and at its lower end the chute 54 extends into the lower end of the housing 31 to provide communication between the latter and the hopper 51. In this manner, any material deposited in the hopper 51 will be delivered by the chute 54 into the lower end of the casing 31 directly adjacent the buckets 26 of the conveyer as they move through the lowermost point of travel in a counter clockwise direction, viewing Fig. 6. A lamp 55 is mounted in any suitable manner directly adjacent the under surface of the chute 54.

The above described device is particularly adapted for use as a display device for advertising purposes to attract the customer's attention. In the embodiment disclosed in the drawings, the hollow casing or delivery unit 13, as above described, is finished on its outer surfaces to repre-

sent a commercial package identical to that in which the substance being displayed is normally marketed. The substance with which the instant device is particularly adapted for use is granulated sugar. It is, of course, to be understood that the display device is equally well adapted for use with any other suitable substance or material.

In the operation of the device, the chain conveyer 25, 26, driven by the motor 16, is adapted to pick up the sugar or other granular material employed at the lower end of the housing 31 and carry the same upwardly to the delivery unit 13. Here the buckets 26 dump the material on the bottom wall 33 of the casing 13 down which it flows to the delivery spout 37, being guided by the converging auxiliary side walls 35 to this point. From the spout 37, the sugar or other granular material flows in a continuous stream into the receiving unit 14 and is deposited upon the circular plate 46 disposed within the bowl 41. After a sufficient quantity of the material has been deposited upon the plate 46 to build up a conical mound thereon, the excess material will flow through the annular aperture 47 onto the conical plate 45 and through the aperture 43 and tube 42 into the hopper 51. From the hopper 51, this excess material will be delivered by the chute 54 into the lower end of the casing 31 to again be picked up by the conveyor 25, 26 and carried upwardly to the delivery unit 13. It will thus be seen that the construction of the receiving unit 14 results in a mound of the granular material being retained therein by the plate 46 at all times to give the appearance of the bowl 41 remaining full without overflowing, despite the continuous stream of material being delivered thereto. At the same time, the continuous stream of the granular material flowing from the delivery spout 37 makes it appear that the delivery unit 13 has an unlimited capacity, while at the same time it is evident that it has a limited and definite volume. Since the sugar or other granular material employed will pick up moisture from the air to reduce its free flowing qualities, the lamp 55 is provided for the purpose of maintaining the granular material in a dry condition. The rear wall of the elongated housing 12 may be made removable therefrom to facilitate the removal of the conveyer 25, 26 and the housing 31 surrounding the latter from the device for the purpose of cleaning or repair. Since the receiving unit 14 is loosely mounted upon the casing 11, it will be apparent that this unit may also be readily removed for the purpose of cleaning or repairing the same.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A display device, comprising a delivery unit in the form of a commercial package, a receiving unit including means mounted therein for retaining only a predetermined quantity of material delivered thereto by said delivery unit, and means for conveying the material delivered to said receiving unit in excess of said predetermined quantity from said receiving unit to said delivery unit.

2. A display device, comprising a hollow base member, a hollow casing extending upwardly therefrom, a delivery unit in the form of a commercial package mounted upon the upper end of said hollow casing, a receiving unit in the form of a bowl mounted upon said hollow base member and including means mounted therein for retaining a predetermined quantity of material delivered thereto by said delivery unit, and means entirely enclosed by said base member, said hollow casing and said delivery unit for conveying the material delivered to said receiving unit in excess of said predetermined quantity from said receiving unit back to said delivery unit.

3. A display device, comprising a hollow base member, a hollow casing extending upwardly therefrom, a delivery unit in the form of a commercial package mounted upon the upper end of said hollow casing, a receiving unit in the form of a bowl mounted upon said hollow base member and including means mounted therein for retaining a predetermined quantity of material delivered thereto by said delivery unit, a hopper mounted within said hollow base member below said receiving unit to receive the material delivered to said receiving unit in excess of said predetermined quantity, and means entirely enclosed by said base member, said hollow casing and said delivery unit for conveying such excess material from said hopper back to said delivery unit.

4. A display device, comprising a hollow base member, a hollow casing extending upwardly therefrom, a delivery unit in the form of a commercial package mounted upon the upper end of said hollow casing, a receiving unit in the form of a bowl mounted upon said hollow base member and including means mounted therein for retaining a predetermined quantity of material delivered thereto by said delivery unit, a hopper mounted within said hollow base member below said receiving unit to receive the material delivered to said receiving unit in excess of said predetermined quantity, a chute connected at one end to the lower end of said hopper and open at the other end and extending angularly therefrom to a point adjacent the bottom of said hollow

base member, and an endless conveyer enclosed entirely within said base member, said hollow casing and said delivery unit for conveying the excess material from said chute to said delivery unit.

5. A display device, comprising a hollow base member, a hollow casing extending upwardly therefrom, a delivery unit in the form of a commercial package mounted upon the upper end of said hollow casing, a receiving unit in the form of a bowl mounted upon said hollow base member and including means mounted therein for retaining a predetermined quantity of material delivered thereto by said delivery unit, a hopper mounted within said hollow base member below said receiving unit to receive the material delivered to said receiving unit in excess of said predetermined quantity, a chute connected at one end to the lower end of said hopper and open at the other end and extending angularly therefrom to a point adjacent the bottom of said hollow base member, an endless conveyer enclosed entirely within said base member, said hollow casing and said delivery unit for conveying the excess material from said chute to said delivery unit, and means disposed adjacent said chute for drying the material passing therethrough.

6. In a display device for providing a continuous stream of granular material flowing from a delivery unit, a receiving unit for receiving such material, comprising a supporting member, a hollow bowl-shaped member mounted on said supporting member, a tubular member extending through said supporting member and into said bowl-shaped member, a substantially conical plate disposed within said bowl-shaped member and surrounding said tubular member, and a second plate disposed adjacent the upper end of said conical plate as a false bottom for said bowl-shaped member and terminating short of the inner surface thereof to provide an annular space through which material delivered to said receiving unit in excess of that which may be retained by said second plate may flow onto said conical plate and into said tubular member.

JOHN A. KERN.
